UNITED STATES PATENT OFFICE.

HENRY THOMAS LYTTLETON, OF MARSHALL, TEXAS.

SPIROMETER.

SPECIFICATION forming part of Letters Patent No. 735,542, dated August 4, 1903.

Application filed January 23, 1903. Serial No. 140,302. (No model.)

To all whom it may concern:

Be it known that I, HENRY THOMAS LYTTLETON, a citizen of the United States, residing at Marshall, in the county of Harrison and State of Texas, have invented a new and useful Spirometer, of which the following is a specification.

This invention relates to an improved spirometer, and has for its object to provide a simple, inexpensive, and efficient device of this character adapted for use by invalids, convalescents, and other persons for exercising the lungs and measuring and indicating the cubic capacity or volume of air expelled from the chest.

This invention consists, in general, in a stationary open tank or vessel having an inclined bottom and filled with water or other liquid and an inverted bottomless vessel or air-receiver of approximately the same shape and size hinged to and fitting within the stationary vessel and carrying a graduated scale or indicator, the stationary vessel being provided with a pipe or tube which extends through the front wall of said vessel and communicates with the air-chamber formed by the hinged receiver, so that when air is expelled from the lungs through the tube it will force the hinged receiver upward and indicate the cubic capacity or volume of air admitted thereto.

The invention further consists in the construction and novel combination and arrangements of parts hereinafter fully described, illustrated in the accompanying drawings, and pointed out in the claims hereto appended.

In the drawings, Figure 1 is a perspective view of the improved spirometer. Fig. 2 is a longitudinal sectional elevation of the same.

Similar numerals of reference indicate corresponding parts in both figures of the drawings.

1 designates a stationary tank or vessel formed of metal or other suitable material open at the top and consisting of the vertical side walls 2, end pieces 3 and 4, and inclined bottom 5. Fitting within the stationary vessel is an inverted vessel or receiver 6, open at the bottom and of approximately the same shape as the stationary vessel. The receiver 6 is removably supported within the stationary vessel 1 by means of hooks 7, engaging

eyes 8, secured to the rear end 3 of the vessel 1, forming a hinged connection and permitting said receiver to rise and fall as the air is admitted to or exhausted therefrom.

The stationary vessel 1 is supplied with a quantity of water or other liquid 9, which nearly fills said vessel and forms a water-seal, preventing the escape of air, as will be more fully explained hereinafter. The front end 4 of the vessel 1 is preferably curved, as clearly shown in Fig. 1 of the drawings, and is provided with a suitable hand or pointer 10, which, in conjunction with a graduated scale 11 on the correspondingly-curved end 12 of the hinged receiver 6, indicates, as the receiver rises, the quantity of air admitted thereto.

A pipe or tube 13 passes through an opening 14 in the front wall of the stationary vessel, one end of which is bent at right angles, forming a vertically-disposed section 14', which extends a slight distance above the water-line and communicates with the air-chamber 15, formed by the receiver 6 when in the closed position. The other end of the pipe or tube 13 is provided with a flexible extension 16, terminating in a mouthpiece 17. A leg or foot 18 is secured in any suitable manner to the rear end 3 of the stationary vessel 1 and serves to support the instrument in a level position.

The water or other liquid is introduced into the stationary vessel by swinging the receiver upwardly on its hinges, and after a sufficient quantity of liquid has been supplied therein the receiver is allowed to assume its normal position within the stationary vessel, the air being forced out through the tube 13 as the receiver descends.

In practice the operator takes a deep inspiration, filling his lungs to their full capacity. The mouthpiece is then pressed to the lips and the air expelled through the tube 13 into the chamber 15, the hinged receiver being raised a distance varying with the quantity of air expelled from the chest and the hand or pointer indicating on the graduated scale as the receiver rises the volume of air admitted to the instrument.

By having the bottom of the stationary vessel inclined it reduces the amount of liquid necessary to the effective operation of the

device and renders the instrument lighter, while it at the same time effectually indicates the volume of air introduced. The receiver being pivotally connected to the stationary vessel at the rear end thereof permits said receiver being thrown back, so as to allow the liquid in the stationary vessel to be replenished when necessary. The receiver may also be detached from the stationary vessel when desired, so that any sediment or deposits accumulated therein may be removed. The leg or support 18 is preferably hinged to the vessel 1, which permits said leg being folded and the instrument compactly arranged for transportation or storage. In some cases a non-congealable liquid, such as oil or glycerin, may be employed instead of water, and various changes in form, proportion, and minor details of construction may be resorted to without departing from the principle or sacrificing any of the advantages of the invention.

Having thus described the invention, what I claim is—

1. A device of the class described, comprising a stationary liquid-containing tank or vessel open at the top and provided with an inclined bottom, a removable inverted receiver pivoted to the tank or vessel and movable within the same, a stationary pointer se-

cured to the liquid-containing vessel, a graduated scale carried by the receiver and coacting with the pointer, an air-conducting tube having its outer end provided with a mouth-piece, the inner end of the tube or pipe being bent at right angles and communicating with the receiver, and means for supporting the tank or vessel.

2. A device of the class described, comprising a stationary liquid-containing vessel open at the top and provided with an inclined bottom, a removable inverted receiver pivoted to the tank or vessel and movable within the same, a stationary pointer secured to the liquid-containing vessel, a graduated scale carried by the receiver and coacting with the pointer, hooks secured to one end of the receiver and adapted to engage eyes secured to the stationary vessel, a leg or support pivoted to the rear end of the stationary vessel, and a pipe or tube leading into the receiver and forming an entrance and exhaust passage for the fluid.

In testimony that I claim the foregoing as my own I have hereto affixed my signature in the presence of two witnesses.

HENRY THOMAS LYTTLETON.
